UNITED STATES PATENT OFFICE.

JOSEPH ARON KARPEL, OF NEW YORK, N. Y.

ELECTRIC SIGN-FLASHER.

1,283,206.

Specification of Letters Patent. Patented Oct. 29, 1918.

Application filed May 14, 1917. Serial No. 168,478.

To all whom it may concern:

Be it known that I, JOSEPH A. KARPEL, a citizen of the United States, and resident of the city of New York, borough of Manhattan, in the county of New York and State of New York, have invented a new and Improved Electric Sign-Flasher, of which the following is a full, clear, and exact description.

10 This invention relates to electrical display devices and has particular reference to variable contact means operated from a single source of power and preferably in a substantially continuous manner.

15 Among the objects of the invention is to improve the details of construction of a rotary multiple make and break device with reference particularly to the prevention of burning out of the contacts by arcing.

20 Another object of the invention is to improve the construction of the several rotary contact members.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

25 Figure 1 is a front elevation, somewhat diagrammatic, of a preferred embodiment of my invention.

Figure 2 is a rear elevation of the same broken away at its middle portion to conserve space.

30 Fig. 3 is a vertical transverse section on the line 3—3 of Fig. 2.

Fig. 4 is a vertical longitudinal detail through several of the contact devices and supporting means.

35 Fig. 5 is a side elevation of one contact member having approximately a 90° contact surface.

Fig. 6 is a side elevation of the master contact member.

40 Fig. 7 is a vertical transverse sectional detail on the line 7—7 of Fig. 3; and

Fig. 8 is a detail perspective view of a portion of the contact member shown in Fig. 5.

45 Referring now more particularly to the drawings I show a variable electric sign

flasher comprising any suitable stationary supports 10 and 11 supported in any suitable position and anchored preferably to a base 12 of slate or its equivalent so as to 60 be well protected from the ground. Journaled in these standards is a shaft 13, of any suitable length, adapted to be rotated at any desired speed and preferably continuously. The means I show for driving this 65 shaft includes a worm gear 14 secured to the shaft with which a power driven worm 15 co-operates. The worm and its shaft are journaled in a bracket 16 adjustable vertically along the standard 10.

70 A series of rotary contact members, shown as seventeen in number by way of illustration, are secured to the shaft 13 and spaced slightly from one another along the shaft. So far as the connection to the shaft, 75 however, is concerned these members are insulated as indicated in Fig. 4 by being gripped by set screws 17 upon thimbles 18 of insulation. One of the end contact members, 19, is referred to herein as the master 80 member and has a continuous contact periphery. (See Fig. 6.) At the opposite end of the series is a contact member 20 whose periphery is divided into four equal contact arcs 21 having as many insulation spacers 85 22 and of the same circumferential extent. All of the contact members 23 between the end members 19 and 20 are of the same general character but differ from one another only in a slight variation in the length of 90 the contact periphery or rim 24.

I wish now to describe more minutely the construction of each of these contact members 23. As will be understood from Figs. 4 and 5 each of them comprises a hub 25, a 95 web portion 26, and an arc shaped contact periphery 24 of any desired extent varying from the shortest in the member adjacent to the member 20 up to the longest, less than a complete circle, in the member adjacent to the master member 19. As will be seen in Figs. 4 and 8 the contact rim portion 24 is materially wider or thicker than the web but the ends thereof are bounded by radial planes 27 which cut through all of the rim 105 and slightly inwardly into the web. All of the web beyond the hub 25 and the rim portion 24 is flat and of uniform thickness throughout and is provided with a circular arc shaped periphery 28. Each of the web 110 portions of each contact member, including the master member, is connected electrically

to the web of the next member by means of a flexible metallic strap 29, these straps being secured to the webs rigidly by means of binding bolts 30. For each contact member 23 there is provided a peripheral insulation device of circular arc shape and of a size and extent complementary to the interrupted contact rim 24. This insulation comprises a pair of blocks 31 having inwardly directed cheek plates 32 fitted flatly against the sides of the web, the outer portions of the blocks being clamped securely together in the central plane of the entire member by binding bolts 33 or their equivalent. The main portions of these blocks fill the circular space provided by cutting away the rim 24, that is to say the two blocks assembled provide an insulation member of exactly the same width and radius as the unbroken portion of the rotary member so that the periphery of the entire member is practically unbroken in a mechanical sense, it being continuous and smooth or without offsets. The circumferential movement of the insulation member is prevented obviously by the flat radial faces at the ends of the contact rim 24. Inward movement is prevented by the radial contact between the body of the block and the periphery 28 of the web, and outward movement of the insulation is prevented by the frictional grip between the two cheek plates thereof and the web and also by contact with the contact brushes referred to below.

At the back of the machine and extending longitudinally from one standard to the other is a bar 34 of slate or other suitable insulation but of sufficient strength for its purpose. A series of brackets 35, one for each rotary contact member and preferably in the same plane thereof, are secured to said bar 34. Each of the brackets has an upwardly and horizontally extending end 35' with a square vertical hole 36 therethrough in the vertical plane of the axis of the shaft 13. This bracket is of metal or other conducting material, and to one of the binding screws securing the same to the bar 34 is connected an electric wire 37.

For each rotary contact member is provided a brush comprising a metal shoe 38 having a polygonal shank 39 slidable vertically in the correspondingly shaped hole 36 and thereby held from rotation, and also including a contact piece 40 preferably of carbon fitted into the shoe and having its lower free end bearing directly upon the periphery of the respective contact member. The extreme upper end of the shank 39 is reduced and screw threaded at 41 upon which are secured a pair of nuts 42. The nuts are adjusted or spaced from the upper face of the bracket end 35' a distance somewhat less than the distance between the lower end of the shoe and the periphery of the contact

member so that when the carbon wears down direct contact between the shoe and rotary contact member will be avoided. A spring 43 surrounds the shank 39 between the shoe and the bracket and serves to force the carbon into constant contact with the periphery of the rotating member. To make the electric connection reliable and constant between the shoe and the bracket 35 I prefer inserting a flexible conducting member 44 attached to the shoe and to the bracket.

Having thus described the principal mechanical features of the device, its operation will be briefly summarized as follows: With the wire 37 leading into the master wheel 19 through its bracket 35 and brush from any suitable source of electrical energy and from the master wheel through all of the others through the constant connections 29 and 30, the circuit from any one of the other wheels or rotary contact members may be carried out from its bracket through its connected wire 37, through any suitable light or sign mechanism to the source of energy, providing of course that the contact rim 24 of that particular rotary contact member is functional or in contact with its brush at that time. If it is desired to illuminate various parts of a sign, for example during different periods of time, said parts of the sign will be respectively connected to those contact members whose contact rims 24 are proportional in a circumferential arc to the lengths of times such parts of the sign are to glow. It is to be noted also in this connection that while I show the intermediate contact members 23 uniformly arranged or stepped throughout the series it is expedient for them to be variously arranged, and with the connections 29 of a flexible nature any one of the members may be adjusted, if desired, circumferentially of the supporting shaft 13 independently of the others. It is also expedient for a plurality of the members 23 to have contact rims 24 of the same length if desired and variously arranged or staggered with respect to one another. Since the current is always through the master wheel 19 and given off from the more or less broken periphery 24 of another wheel through a brush whose contact block bears constantly and squarely upon the cylindrical periphery of the contact member, there is no possibility of arcing or premature destruction of any part of the device. The remarks just made referring to the contact members 23 apply also to the member 20, this member differing from the others only in having a plurality of contact rims 21 and corresponding to the several contact rims 24 of the other members.

I claim:

The herein described electric sign flasher comprising a series of coaxial rotary con-

tact members, each member having a smooth circular periphery, the peripheries of the several contact members being provided with blocks of insulation of varying circumferential extents and a series of contact brushes coöoperating with the several smooth practically unbroken peripheries aforesaid, each brush comprising a shoe having a polyg-

onal shank whereby it is held from rotation, spring means acting upon the shoe tending to force it in a radial direction toward its contact member, and a block of carbon carried by the shoe and having direct contact with the smooth periphery aforesaid. 10

JOSEPH ARON KARPEL.
